UNITED STATES PATENT OFFICE.

ALFRED P. BABCOCK, OF BROOKLYN, NEW YORK.

DESIGN FOR A BOTTLE.

SPECIFICATION forming part of Design No. 24,578, dated August 20, 1895.

Application filed May 23, 1895. Serial No. 550,450. Term of patent 7 years.

To all whom it may concern:

Be it known that I, ALFRED P. BABCOCK, a citizen of the United States, and a resident of Brooklyn, in the county of Kings and State 5 of New York, have invented a certain new and original Design for Bottles, of which the following is a specification.

Referring to the drawings, in which like letters of reference denote corresponding parts 10 in both of the views, Figure 1 is a front view of a bottle embodying my design, and Fig. 2 is a sectional view on the line 2 2 of Fig. 1.

The leading feature of my invention is a perfumery-bottle which is made in form and 15 configuration and ornamented and embellished substantially in the manner illustrated in the accompanying drawings.

On the lower portion C of the design I provide feet c, above which is a scalloped panel 20 c', and above this panel is a representation of the lower part of a stove, comprising a door c², the ribs c³, and other suitable ornamenta-

tion. The middle portion A of the design is provided with representations of windows a and a door a', and it also has an annular ring 25 a² and an ornamental panel a³. The upper portion B is provided with a ribbed section b, a panel b', and a row of round projections b², and is ornamented by a cap b³, having an ornamental base b⁴.

The outline and ornamentation of the bottle 30 make a most attractive article, which is pleasing in appearance and of convenient shape.

Having thus fully described my design, what I claim is—

The design for a bottle, substantially as 35 herein shown and described.

Signed at New York, in the county of New York and State of New York, this 22d day of May, A. D. 1895.

ALFRED P. BABCOCK.
